CLAIM

The ornamental design for a combined sports cap and light therefor, as shown and described.

DESCRIPTION

FIG. 1 is a front elevational view of the combined sports cap and light therefor showing my new design;

FIG. 2 is a rear elevational view thereof;

FIG. 3 is a left side elevational view thereof, with the wires broken away to indicate indeterminate length;

FIG. 4 is a right side elevational view thereof;

FIG. 5 is a top plan view thereof; and,

FIG. 6 is a bottom plan view thereof.
